Fig. 1.

UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

GARAGE.

Application filed June 11, 1927. Serial No. 198,096.

This invention relates to buildings and more particularly to storage buildings such as garages of the type wherein the several floors are connected by ramps over which

5 vehicles may be driven from floor to floor in order to reach their respective storage spaces. The main objects of the invention are to improve and simplify the structure of such a building and to provide an easy ascent for 10 the vehicular traffic without reducing the storage capacity of the floors.

Other objects will appear hereinafter.

In the drawings:

15 Fig. 1 is a horizontal section taken on the line 1—1 of Fig. 2;

Fig. 2 a vertical section taken on the line 2—2 of Fig. 1; and

Fig. 3 a vertical section taken on the line 3—3 of Fig. 2.

20 The building, in the present instance, has a rectangular plan and is formed with side walls 1 and 2 and end walls 3 and 4. The walls enclose a bank of superposed storage and driveway floors 5 which cover almost the 25 entire ground plan of the building. The floors 5 incline upwardly from the end wall 3 clear to the end wall 4 and are preferably parallel to each other.

At the center of the building is a group of 30 superposed ramps 6 which provide driveway connections between the various floors. These ramps incline oppositely to the direction of inclination of the floors and extend parallel to the side walls 1 and 2. Each ramp is dis-

35 posed between a pair of adjacent floors and is connected directly to them to provide a straight, direct, vehicular path from one floor to the other. Each floor, with the exception of the lowermost one, is formed with an open-

40 ing 7 directly over the ramp, leading upwardly to it, and of substantially the same size and shape as the ramp. The floor openings 7 provide clearance for the vehicles passing over the ramps and permit them to pass

45 through the floors and out upon the inclined surfaces thereof. The longitudinal edges of the openings 7 and the corresponding edges of the ramps are provided with suitable curbing 8. The ramps are considerably shorter than the inclined length of the floors 5 and

50 terminate at points spaced inwardly material distances from the end walls 3 and 4. The

ramp ends are spread outwardly beyond the curbing 8 as indicated at 9 and merge gradually with the floor surfaces along curved 55 lines.

Each floor area is laid out to provide two longitudinal driveway spaces 10 and 11 extending from the wall 3 to the wall 4 and located midway between the ramps 6 and the 60 side walls 1 and 2. These driveways extend parallel to the walls 1 and 2. The floors are also provided with transverse driveways 12 and 13 which connect the longitudinal driveways and extend across the opposite ends 9 of 65 the ramps. Individual vehicle storage spaces 14 are laid out upon the floor areas along both sides of the driveways 10 and 11. These storage spaces extend along the length of both side walls 1 and 2, along the opposite 70 sides of the ramps 6, and cover the areas between the transverse driveways 11 and 12 and the end walls 3 and 4. The ramps are thus surrounded by driveways and storage spaces upon each floor. The individual storage spaces are preferably disposed transversely of the inclined length of the floors so that the stored vehicles will not accidentally roll out of their respective spaces.

The end wall 3 is provided with a doorway 80 15 which opens directly into one end of the driveway 10 of the lowermost floor. A vehicle may be driven in through the doorway 15, upwardly along the inclined driveway 10, turned to the right into the transverse driveway 13 and then up one of the ramps 6 and through the opening 7 to the next floor above. At this floor the vehicle may be driven to the right, out through the transverse driveway 11, into the driveway 10, and up the incline 85 90 of the latter to the end of the next ascending ramp. In this manner the vehicle may be driven from the lowermost floor to the uppermost one, or to an intermediate floor, to reach its respective storage space. All of 95 the turns made by the vehicle in its ascent are right hand turns and it travels over a path which is substantially spiral and ascends almost continuously.

The ramps 6 are sufficiently wide to accommodate two streams of traffic side by side. A descending vehicle is driven down each ramp and successively through the transverse driveway 13, the inclined driveway 11 and the

transverse driveway 12 to the next descending ramp. When the vehicle reaches the lowermost floor it is driven down the inclined driveway 11 and out through a doorway 16 formed in the end wall 3. The vehicle is required to make only right hand turns in its descent. The path of travel of the vehicle is substantially spiral and descends almost continuously throughout its length. There is no intersection of the ascending and descending streams of traffic at any point and the vehicles can, therefore, be driven rapidly from floor to floor with a minimum of confusion and risk.

The ascent passages at the center of the building are laterally open along their length. This also facilitates the rapid and safe travel of the vehicles. The ramp driveways and the floor driveways are mutually exposed across the curbing 8. A driver of a vehicle upon any of the floors may easily observe the traffic upon a ramp which he is approaching and govern the speed of his vehicle to avoid collision. From any of the floor driveways the adjacent ramp pasageways are exposed to view along most of their length. Drivers upon the ramps have the same advantage. The floor driveways 10, 11, 12 and 13 are exposed to their view and they can observe the traffic thereon and also see if there are any cars being backed out of the storage spaces and into their path. This easy visibility materially lessens danger and confusion, avoids the necessity of extreme caution, and enables a driver to speed up his vehicle when he sees that his path is clear for a long distance ahead and around the turns of the spiral.

The inclination of the floor 5, the arrangement of the ramps longitudinally of the inclined direction of the floors, and the inclination of the ramps oppositely to the inclination of the floors, enables both the floors and the ramps to share the ascent grade. The grade is thus made longer and less steep. This increased length of the grade entails no additional sacrifice of storage space owing to the fact that it occurs in the floor driveway spaces 10 and 11 which are necessarily provided to render the storage spaces accessible. The rise in the driveways 10 and 11 in the distance between the opposite ends of the ramps is sufficient to materially reduce the necessary inclination of the ramps and provide a low and almost continuous grade for the inter-floor traffic. The outward spread of the ramp ends 9 along curved lines merges the ramp grade laterally with the floor and enables the vehicles to be driven from the driveways 12 and 13 to the ramps, or vice versa, evenly and without objectionable twisting strains when they make the turns.

What I claim is:

1. A storage building structure comprising a plurality of superposed inclined storage and driveway floors; and a plurality of ramps directly connecting said floors in suc-

cession, each ramp providing driveway connection through one floor and from a high point in one floor to a low point on the next higher floor, the floor areas extending entirely around the ramps.

2. A storage building structure comprising a plurality of superposed storage and driveway floors all inclined in the same direction and covering substantially the entire enclosed storage area of the building; and a plurality of superposed ramps inclined oppositely to said floors and directly connecting the latter in succession to provide driveway connection therebetween through said floors, said ramps being within the bounds of the floor areas.

3. A storage building comprising a plurality of superposed storage and driveway floors all inclined in the same direction; and a plurality of superposed ramps inclined oppositely to said floors and directly connecting the latter in succession to provide driveway connections therebetween, said ramps being materially shorter than the inclined lengths of the floors and terminating material distances inwardly from the ends of the floors, the floor areas extending entirely around the ramps and each floor being provided with driveway spaces extending entirely around the ramps and leading to the ramps connected to it, and with storage spaces arranged along said driveway spaces.

4. A storage building comprising a plurality of superposed storage and driveway floors all inclined in the same direction; and a plurality of ramps inclined oppositely to said floors and directly connecting the latter in succession to provide driveway connections therebetween, said ramps being materially shorter than the inclined lengths of the floors connected to them, and each floor being provided with a driveway space connecting the ends of the ramps leading to the floor and with storage spaces arranged along said driveway space.

5. A storage building comprising a plurality of superposed storage and driveway floors all inclined in the same direction; and a plurality of ramps inclined oppositely to said floors, and connecting the latter in succession to provide driveway connections therebetween, each floor extending entirely around its connected ramps and being provided with driveway spaces extending entirely around the ramps and leading to them, and with storage spaces arranged along said driveway spaces at opposite sides of the ramps.

6. A storage building structure comprising a plurality of superposed storage and driveway floors all inclined in the same direction; and a plurality of superposed ramps inclined oppositely to said floors and directly connecting the latter in succession to provide driveway connections therebetween the

passageways over the ramps being laterally exposed along their length to the adjacent floors.

7. A storage building comprising a plurality of superposed storage and driveway floors all inclined in the same direction; and a plurality of ramps inclined oppositely to said floors and connecting the latter in succession to provide driveway connections therebetween, each floor extending entirely around its connected ramps and being provided with driveway spaces extending entirely around the ramps and leading to them, and with storage spaces arranged along said driveway spaces at opposite sides of the ramps, the passageways over the ramps being laterally exposed along their length at both sides to the adjacent floors.

8. A storage building comprising a plurality of superposed parallel storage and driveway floors all inclined in the same direction and formed with vertically alining openings through their inclined areas; a plurality of straight superposed parallel drive-

way ramps inclined oppositely to said floors, 25 connected directly to the latter in succession through said openings and formed to accommodate an ascending stream of traffic and a descending stream side by side, said ramps being materially shorter than the inclined 30 lengths of the floors connected to them, each floor extending entierly around its connected ramps and provided with longitudinal driveway spaces extending parallel to the ramps at opposite sides thereof and beyond the ends 35 of the ramps, storage spaces along the lengths of said spaces and transverse driveway spaces connecting each end of each ramp with said longitudinal driveway spaces to provide a substantially spiral vehicular ascent path 40 and a separate substantially spiral vehicular descent path from floor to floor, the passages over the ramps being laterally exposed along their lengths at both sides to the adjacent floors.

In testimony whereof I hereunto affix my signature.

FERNAND E. D'HUMY.
